UNITED STATES PATENT OFFICE

JOSEPH DE LEON, OF CHICAGO, ILLINOIS

DESIGN FOR A GAME BOARD

Application filed September 24, 1931. Serial No. 41,209. Term of patent 14 years.

To all whom it may concern:

Be it known that I, JOSEPH DE LEON, a citizen of Mexico, residing at Chicago, in the county of Cook and State of Illinois, have invented a new, original, and ornamental Design for a Game Board, of which the following is a specification, reference being had to the accompanying drawing, forming part thereof.

The figure is a plan perspective view of a game board, showing my new design.

I claim:

The ornamental design for a game board, as shown.

JOSEPH DE LEON.
